UNITED STATES PATENT OFFICE

2,507,887

ELEVATOR

Wallace E. Cheney, Milwaukee, Wis.

Application November 17, 1947, Serial No. 786,537

13 Claims. (Cl. 187—12)

1

My invention relates to elevators, and more particularly to elevators of the type in which a car runs along inclined rail means for at least part of its travel, and the principal object of my invention is the improvement of apparatus of these types.

A more specific object of my invention is the provision of an elevator which is adapted for use with stairs in general, and more particularly, which may be utilized with stairs comprising one or more flights and wherein the rail means is both inclined and parallel with the horizontal.

Other objects will appear hereinafter as the description of the invention proceeds.

In certain respect, the present invention provides improvements to the construction shown in Patent 2,212,388, granted to me August 20, 1940.

In the drawings accompanying this specification and forming a part of this application, there is shown, for purposes of illustration, an embodiment which my invention may assume, and in these drawings:

Figure 1 is a broken fragmentary elevational view, showing an elevator embodying my invention, with the car on a horizontal portion of the track means,

Figure 2 is a fragmentary elevational view showing the car on an inclined portion of the track means,

Figure 3 is a fragmentary sectional view corresponding generally to the line 3—3 of Figure 1,

Figure 4 is a perspective view of a carriage used in the embodiment of the invention herein shown,

Figure 5 is another perspective view of the carriage, viewed from a different position,

Figure 6 is a fragmentary plan view of the carriage,

Figure 7 is a fragmentary end view of the carriage, and

Figure 8 is a fragmentary sectional view corresponding generally to the line 8—8 of Figure 6.

Referring particularly to Figures 1 and 2, the elevator herein disclosed comprises a car 10 movable along track means 11. The car 10 is herein shown as comprising a chair, having a seat 12 and a back 13, and arm rests or the like (not shown) if desired. However, it is to be understood that the term "car" as used herein is intended to cover any other suitable conveyance.

The rail means 11 is herein disclosed as comprising two parts 14 and 15, each of which may be formed of one or more sections. As here shown, the rail part 14 comprises a horizontal portion 14a, which may have an I-beam cross-section, an inclined portion 14b which may have an inverted T-cross-section, and a lower combined inclined and horizontal portion 14c which may have an I-beam cross-section.

2

The upper part 15, as here shown, comprises a horizontal portion 15a which may be of T section and with the extremity of its stem welded to the upper flange of the portion 14a, an inclined portion 15b which may be merely a flange welded to the extremity of the stem of the portion 14b, and a lower horizontal portion 15c which may be of T section and welded to the upper flange of the portion 14c. The upper flanges of the portions 14a and 14c stop short of contact with the portion 15b, to form passages 16 for a purpose which will appear later.

It will be understood that the track means 11 may be formed in any other suitable manner, with attention given to the spacing of the flanges of the portions 15a, 15b and 15c with respect to the adjacent portions 14a, 14b and 14c.

A rack 17 is suitably secured to the lower flange of the part 14, and closely follows the longitudinal formation of this flange.

The car 10, as herein disclosed, comprises a housing 18, having an enlarged portion 19 supporting the seat 12 and back 13, and a depending restricted portion 20 terminating in a gear box 21.

Suitable power providing means, such as an electric motor 22 (see Figure 1), may be contained within the enlarged portion 19 of the housing 18. The shaft of the motor 22 may carry a pinion 23 which meshes with a gear 24 carried at the upper end of a shaft 25. The shaft 25 may be journaled in suitable bearings (not shown) carried by the restricted portion of the housing 18.

The lower end of the shaft 25 may carry a worm 26 which meshes with a worm gear 27, the latter driving a shaft 28 which carries a pinion 29. The pinion 29 is adapted to mesh with the rack 17, and to move the car along the track means 11, in either direction, in accordance with the direction of rotation of the motor shaft.

Operation and control of the elevator may be effected in any suitable manner and by any suitable means. As an example, reference is made to my aforementioned patent, wherein a control system is described which may also be used in this case.

A carriage 35 serves as a means of connection between the housing 18 and the rail means 11, and as herein shown, the carriage 35 comprises spaced angles 36 and 37 connected together by means of a transversely extending channel 38 which is welded or otherwise suitably secured to respective angles.

Spaced from respective angles 36, 37 are plates 39 and 40, the plate 39 being held in spaced relation by means of end pieces 41, and the plate 40 being held in spaced relation by means of an end piece 42 and an intermediate piece 43. The

end pieces 41 and 42 and the intermediate piece 43 are welded or otherwise suitably secured to respective angles 36, 37, and the end pieces are formed with recesses 44 to insure free passage of the rail means 11, as will later appear.

Extending transversely between the angles 36, 37 is a shaft 45 (see Figure 8), which has its ends extending through apertures in facing legs of the angles. A sleeve 46 and a roller 47 are rotatively mounted on the shaft 45 in the space between facing legs of the angles 36, 37, the sleeve 46 occupying a greater portion of this space. The roller 47 is preferably journalled by means of a ball-bearing race, as shown, to reduce friction losses. Welded, or otherwise suitably secured to the sleeve 46, is a connecting plate 48 which is adapted to be bolted to the housing 18, to connect the housing and the carriage 35. The plate 48 is formed with a cut-out 49 to provide clearance for the roller 47.

Extending transversely with respect to the shaft 45, and through apertures in the other legs of the angles 36, 37 and the corresponding plates 39, 40, are shafts 55, 56. The upper ends of the shafts 55, 56, as viewed in Figures 1 through 5 and 8, are secured to respective extremities of the shaft 45, as by means of bolts 57.

From the foregoing, it will be appreciated that the carriage 35 may swing about the axis of the shaft 45, and relative to the sleeve 46 and connecting plate 48, and this is clearly indicated in Figures 1 and 2.

Journalled on the shaft 55, within the space between the angle 36 and the plate 39, is a roller 58 which comprises a hub portion 59 enclosing a thrust bearing 60, and spaced-apart annular enlargements 61 defining therebetween a tapered groove 62. Journalled on the shaft 56, as by means of needle bearings 63, within the space between the angle 37 and the plate 40, is a roller 64 which comprises a hub 65 and a single annular enlargement 66.

Spaced from the shaft 55 is a shaft 70 which extends through apertures in the leg 36 and the plate 39. A cotter key 71 extends through aperture in the shaft 70, and the legs of the key 71 also extend through an aperture in the leg of the angle 36 before being spread, as best shown in Figures 6 and 7, so as to hold the shaft 70 in proper position and against rotation.

Journalled on the shaft 70, within the space between the angle 36 and plate 39, is a roller 72, comprising a hub 73 and spaced-apart annular enlargements 74, defining therebetween a tapered groove 75. In some cases, as illustrated best in Figures 1 and 2, it is preferable to construct the rollers 58 and 72 so that the groove 75 is somewhat wider than the groove 62, although this is not essential.

Extending through elongated apertures 76 formed in the angle 37 and plate 40 is a shaft 77, and journalled on this shaft, between the angle 37 and the plate 40 is a cylindrical roller 78. The extremities of the shaft 77 extend beyond opposed outer surfaces of the angle 37 and plate 40, and each extremity is apertured to receive one end of a spring rod 79. The opposite ends of the spring rods 79 are anchored, by means of a set of screws 80, in respective lugs 81 carried by the angle 37 and the plate 40.

The rollers 58 and 64 are in opposed relation, as are the rollers 72 and 78, the construction being such that the extremities of the flange of the portions 15a and 15c, and the flange 15b, are adapted to be received between opposed rollers, as best seen in Figures 3, 6, 7, and 8. The

function of the spring rods 79 is to constantly urge the roller 78 toward the roller 72, so that the extremities of the flanges of portions 15a, 15b, and 15c, are normally engaged by rollers 72 and 78. The rollers 58 and 64 may be so constructed and positioned that a slight space may exist between these rollers and the flanges, although this is not essential to the invention.

In operation, as the car 10 is driven along the track means 11 through coaction of the driven gear 29 with the rack 17, the aforementioned rollers coact with the flanges of the portions 15a, 15b, and 15c to maintain the housing 18 erect, regardless of whether the car is travelling along a horizontal portion of the track means or an inclined portion of this track means. This is accomplished by properly spacing the flanges of portions 15a, 15b, and 15c with respect to the rack 17, and properly positioning the drive gear 29 with respect to the carriage 35. The passages 16 in the track means permit the carriage 35 to freely move along the entire track means.

In use, a person P normally sits on the seat 12, and at least a greater part of the weight is distributed about the center-line CL of the car 10. Through use of my invention, however, it is not important that the person be so seated that his weight is distributed evenly about the center-line CL, as will appear.

With a person seated on the car 11, a certain amount of the weight is taken by the drive connection between the gear 29 and the rack 17. When on the horizontal, the weight pressure absorbed by the carriage 35 is principally carried through interengagement of the rollers 64 and 72 with the horizontal portions of the flanges of the track part 15. If power is applied to the gear 29, the roller 47 maintains the car 10 erect if moved to the right, as viewed in Figure 1. If the car 10 is moved to the left, as viewed in Figure 1, interengagement of the annular enlargements on the rollers 58 and 64 with the horizontal portions of the flanges of the track part 15 maintains the car 10 erect.

On an incline, such as is the case in Figure 2, the pressure caused by the weight of a person is again carried in certain amount by the gear 29 and rack 17. In this case, however, the pressure on the carriage 35 is carried by interengagement of roller 47 and the annular enlargements on rollers 64 and 72 with the flange 15b. In some cases, an annular enlargement on roller 58 engages with flange 15b, and assists in carrying the load.

In going over a bend, such as the bends between horizontal and incline, roller 72, being some distance from the pivot shaft 45, causes the carriage 35 to pivot, as seen in Figure 2, so that the carriage follows the track without binding.

When going over a curve, such as the top bend, as viewed in Figure 1, roller 58, because of action of its thrust bearing, assists in causing the carriage 35 to follow the track. At the bottom bend, roller 47 assumes a considerable amount of the weight, so that the carriage 35 may freely follow the curve in the track.

The spring rods 79 provide limited spring motion to the shaft 77, so that the roller 78 mounted on this shaft urges tight connection between it, roller 72, and the corresponding extremities of the flange of track part 15. This compensates, to some extent, for differences in rail widths. When going over a curve, roller 78 will yield, thus permitting the adjacent portion of the flange part 15 to be at a small angle to the groove

in roller 72. When going around horizontal bends, especially short radius bends, the roller yields sufficiently to allow for the increase in distance from one side of the track to the other side.

The grooves in the rollers 58 and 72 are tapered out to assure contact with the rail flange as near to the bottom of the groove as possible, thus avoiding excessive wear between the flange and the rollers. As the rail flange wears, the roller 78, being on a spring mounted shaft, maintains the adjoining part of the carriage 35 with a good fit on the rail flange.

Inasmuch as the distance between the center lines of rollers 58 and 72 has purposely been held to a small amount, the car 10 may be freely moved along a track means 11, regardless of whether or not such track means has horizontal or vertical bends, or a combination of both.

From the foregoing, it will be apparent to those skilled in the art that I have accomplished at least the principal object of my invention, and it also will be apparent to those skilled in the art that the embodiment herein described may be variously changed and modified, without departing from the spirit of the invention, and that the invention is capable of uses and has advantages not herein specifically described; hence it will be appreciated that the herein disclosed embodiment is illustrative only, and that my invention is not limited thereto.

I claim:

1. An elevator, comprising: a car; track means, over which said car is adapted to travel, said track means having portions at an angle with respect to each other; and carriage means, connecting said car with said track means, and including a pivot joint providing for movement of said car along track portions of different angularity, said carriage means comprising roller means spaced from said pivot joint and engageable with said track means.

2. An elevator, comprising: a car; track means, over which said car is adapted to travel, said track means having portions at an angle with respect to each other; and carriage means, connecting said car with said track means, and including a pivot joint providing for movement of said car along track portions of different angularity, said carriage means comprising roller means positioned substantially adjacent to said pivot joint and engageable with said track means, and roller means spaced from said pivot joint and engageable with said track means.

3. An elevator, comprising: a car; track means, along which said car is adapted to travel, and having opposed and side surfaces; and carriage means, connecting said car with said track means, and comprising a plurality of rollers, certain of said rollers being adapted to engage both of said opposed surfaces, certain of said rollers being adapted to engage only one of said opposed surfaces, and certain of said rollers being adapted to engage a side surface, said last named of said rollers being resiliently urged toward engagement with said side surface.

4. An elevator, comprising: a car; track means, along which said car is adapted to travel, and having longitudinal portions at an angle to each other, said track means including flange means having opposed surfaces at each side and a side surface at each side; and carriage means, connecting said car with said track means, and including a pivot joint and three rollers adjacent to said pivot joint, one of said three rollers being

adapted to engage either one of the opposed track surfaces at one side of said flange means, the other of said three rollers being adapted to engage only one of the opposed track surfaces

5 at the other side of said flange means, and the third roller being adapted to engage only the opposite side of the opposed track surfaces at said other side of said flange means, and a pair of rollers spaced from said pivot joint, one of said 10 pair of rollers being engageable with either one of the opposed track surfaces at one side of said flange means, and the other of said pair of rollers being adapted to engage only a side surface of said track means at a side opposite the side engaged by said first named pair of rollers, said last named of said pair of rollers being spring mounted to urge said pair of rollers into engagement with said track means.

5. An elevator, comprising: a car; track means, 20 comprising an upwardly angled portion; carriage means adapted to travel along said track means; a pivot connection between said car and said carriage means whereby said car and said carriage means may assume different angular relations during travel of said carriage means along said track means; and means for effecting relative shifting of said car and said carriage means in accordance with the angularity of said track means.

30 6. An elevator, comprising: a car; track means of non-planar formation throughout its longitudinal extent; carriage means adapted to travel along said track means; means connecting said car to said carriage means, so constructed and arranged that said car and said carriage means may be shifted to various angular relative positions; roller means engageable with said track means for holding said carriage means to movement along said track means; and other roller 40 means engageable with said track means to effect relative shifting of said car and said carriage means in accordance with the configuration of said track means.

45 7. An elevator for use with stairs and the like, comprising: track means extending longitudinally of and following the course of the stairs; a car adapted to carry a load, such as a person; carriage means movable along and adapted to follow the course of said track means; means connecting said car to said carriage means and providing relative tilting movement therebetween; roller means engageable with said track means for holding said car in generally upright 55 position in all movements of along said track; and roller means engageable with said track means for causing tilting action between said car and said carriage means in accordance with the course of said track means whereby said 60 carriage means may follow the course of said track means while said car is in generally upright relation.

8. An elevator for use with stairs and the like, 65 comprising: track means comprising a gear rack generally following the course of the stairs and flange means held in spaced relation with respect to said gear rack and also generally following the course of the stairs; a car adapted to carry a load, such as a person, having a motor 70 driven gear wheel meshing with said gear rack, said gear wheel being generally in alignment with the load carrying portion of said car and adapted to carry at least some of the load; carriage means movable along and adapted to follow the course of said flange means; means con-

necting said car and said carriage means and providing relative tilting movement therebetween; first roller means carried by said carriage means in position off-set with respect to alignment with the load carrying portion of said car, said first roller means being engageable with the upper surface of said flange means and being adapted to carry at least some of the load; second roller means engageable with opposite side margins of said flange means to prevent tilting of said car laterally of said track means; and third roller means engageable with said flange means for causing tilting action between said car and said carriage means in accordance with the course of said flange means, whereby said carriage means may follow the course of said flange means while said car is in generally upright relation.

9. An elevator for use with stairs and the like having inclined and horizontal portions, comprising: track means comprising a gear rack generally following the course of the stairs and flange means held in spaced relation with and generally overlying said gear rack and also generally following the course of the stairs; a car adapted to carry a load, such as a person, having a motor driven gear wheel meshing with said gear rack, said gear wheel being generally in alignment with the load carrying portion of said car and adapted to carry at least some of the load; carriage means movable along and adapted to follow the course of said flange means; a pivot connection between said carriage means and said car, providing for relative tilting of said car and said carriage means; first roller means co-axial with said pivot connection and engageable with the upper surface of said flange means and being disposed off-set with respect to alignment with said gear wheel and adapted to cooperate therewith to carry at least some of the load and to maintain said car in generally upright relation in all positions of said car along said track means; second roller means carried by said carriage adjacent to said pivot connection and having flanges engageable with upper and lower surfaces of said flange means and adapted to hold said first roller means generally in engagement with the upper surface of said flange means; and third roller means carried by said carriage means in position spaced from said second roller means and having flanges engageable with upper and lower surfaces of said flange means whereby said carriage means is tilted in accordance with the course of said flange means, thus permitting said car to remain in generally upright relation.

10. In an elevator for use with stairs which include a curved portion: flange means providing a track following the course of the stairs; carriage means movable along said track; a pair of first roller means, at least one having flanges engaging upper and lower surfaces of said flange means and each of said roller means being engageable with a respective one of the opposite marginal surfaces of said flange means whereby said carriage is held to movement along said track; a pair of second roller means spaced from said first roller means and forming a pilot for guiding said carriage in accordance with the configuration of said track, each of said second roller means being engageable with opposite side marginal surfaces of said flange means, and at least one of said second roller means being resiliently urged toward the other roller means so that said second roller means may be yieldably spread apart when said carriage means passes along a curved portion of said track

and thus prevent binding of said carriage means on said track.

11. In an elevator including a car for use with stairs which are horizontal, inclined and curved, said car being adapted to be held in generally upright relation: flange means providing a track following the course of the stairs; carriage means movable along said track and having pivoted connection with said car so that said carriage means may tilt with respect to said upright car; a pair of first roller means, at least one having flanges engaging upper and lower surfaces of said flange means and each of said roller means being engageable with a respective one of the opposite side marginal surfaces of said flange means, whereby said carriage is held to movement along said track; a pair of second roller means spaced from said first roller means and forming a pilot for guiding said carriage in accordance with the configuration of said track, at least one of said second roller means having flanges engaging upper and lower surfaces of said flange means to cause pivotal movement of said carriage means with respect to said car when said carriage means passes along horizontal and inclined portions of said track, each of said second roller means being engageable with a respective one of the opposite marginal surfaces of said flange means, and at least one of said second roller means being resiliently urged toward the other roller means so that said second roller means may be yieldably spread apart when said carriage means passes along a curved portion of said track and thus prevents binding of said carriage means on said track.
12. An elevator for stairs and the like, comprising: flange means providing a track extending longitudinally of and following the course of the stairs; carriage means movable along said track and comprising first means engageable with said flange means at opposite side margins for holding said carriage means to movement along said track, and comprising also second means spaced from said first means and engageable with said flange means at opposite side margins and providing a pilot for said carriage means whereby said carriage means is caused to follow the configuration of said track means.
13. An elevator for stairs and the like, comprising: flange means providing a track extending longitudinally of and following the course of the stairs; carriage means movable along said track and comprising first means engageable with said flange means at opposite side margins for holding said carriage means to movement along said track, and comprising also second means spaced from said first means and engageable with said flange means at opposite side margins and providing a pilot for said carriage means whereby said carriage means is caused to follow the configuration of said track means, said second means being yieldably pressed into engagement with said flange means so that they may yieldably spread to prevent binding of said carriage means when negotiating bends in said track.

WALLACE E. CHENEY.
